UNITED STATES PATENT OFFICE.

EDWARD M. E. HANSEN, OF ST. LOUIS, MISSOURI.

CHEMICAL FIRE-EXTINGUISHER.

1,165,502.

Specification of Letters Patent.

Patented Dec. 28, 1915.

Application filed August 25, 1913, Serial No. 786,545. Renewed September 30, 1915. Serial No. 53,425.

To all whom it may concern:

Be it known that I, EDWARD M. E. HANSEN, a citizen of the United States, residing at St. Louis city in the State of Missouri, have invented certain new and useful Improvements in Chemical Fire-Extinguishers; and I do declare the following to be a full, clear, and exact description of the invention, such as will enable others skilled in the art to which it appertains to make and use the same.

This invention relates to fire extinguishers, and more especially to those involving the mixture of chemicals by means of which water is impregnated with a fire-subduing gas; and the present invention is an improvement on my former patent numbered 957,054 and issued May 3, 1910.

The object of this invention is to effect various improvements in the construction and hence in the results capable of being attained with the device heretofore patented, and this object is secured by changes in and elaborations of the former structure, as will be explained in the following specification and claims, and as shown in the drawings wherein—

Figure 1 is a side elevation of this apparatus complete, the main tank being broken away to show parts on the interior; Fig. 2 is an end elevation of the apparatus, and Fig. 3 is a cross section on the line 3—3 of Fig. 1. Fig. 4 is a sectional detail of the cap for the filling opening in the acid reservoir.

In the drawings the numeral 1 designates the main tank and 2 the charging cylinder disposed in an upright position through the top of said tank as shown and having a water-inlet port 3 through its side above said tank 1. The cylinder is closed at its upper end by a cover 4 in which at 5 is swiveled the lower end of a screw 6 having a turning wheel 7 at its upper end provided with handles 8. The screw passes through a threaded aperture at the mid-length of a supporting bar 9 which is pivoted at one end at 10 on an upright post 11 rising from the cylinder 2, and is notched at 12 near its other end so that it may engage a screw rising from another post 13, and may be held thereon by means of a nut 14. By this construction the screw may be retracted by turning the hand wheel, and when the cover 55 is raised off the upper end of the cylinder the latter can be charged with the bicarbo-

nate of soda in a well known manner. The supporting bar 9, pivoted at one end and removably clamped at the other, is for swinging the cover aside when it is desired to gain direct access to the interior of the cylinder.

The water inlet pipe is shown at 18, its inner end communicating with the main tank at the point 17, and in said pipe is an elbow 22 from which leads a by-pass pipe 21 that extends upward and communicates with the water inlet port 3 in the side of the cylinder 2—a cut off valve 23 being disposed within said by-pass to regulate the flow of water into the soda cylinder. The inner end 17 of the inlet pipe enters the main tank below a perforated plate 16 disposed across the same at a slight distance above its bottom as in my former patent; and the outlet pipe 19 has a perforated hood or strainer 20 over its inner end as shown. The bottom of the tank may have a clean out opening covered by a cap 15 as illustrated. The general and specific construction of parts thus far described may be the same as formerly patented to me or may differ therefrom in unimportant details; and no claim is laid on the features bearing reference numerals smaller than 30.

Coming now more particularly to the details not found in my former patent, I preferably make the charging cylinder in two members as seen in Fig. 3, connected at their meeting ends as by threads 31 and by a flange 32 on one member through which pass screws 33 into an annular casting 34 mounted on the main tank 1, permitting ready separation of parts, and giving access to the interior of the main tank when desired. Also I preferably provide said main tank with a man-hole, consisting of an annular casting 35 as seen in Fig. 1 closed by a cap 36 screwed into place or otherwise held within the casting, and by preference I mount a pressure gage 37 on this cap. If the man-hole be of sufficient size the specific form of connection between the two members of the soda cylinder need not be employed, although both details might be adopted if desired. At the rear end of the perforated plate 16 I find it advisable to locate an upright baffle 38 extending across the interior of the tank 1 whereby the rush of water through the pipe 17 will not wash the soda too rapidly out the outlet—the disposition of this baffle tending rather

to create eddies in the water as indicated by the arrows in Fig. 1. I use a check valve 27 at the lower or outlet end of the cylinder, as in my prior patent, but do not wish to be limited to the specific form of this valve. In the present case I have shown it as having a pivotal support and as being weighted so that it will drop automatically onto an oblique or inclined seat. In the water pipe 18 I dispose a check valve 38 of any suitable type, and between the elbow 22 and the inner end 17 of said water pipe I dispose a water regulating valve 39 of any suitable type. Another regulating valve 30 may be placed in the outlet pipe 19. It is hardly necessary to say that if this device is built on a small scale as for towns and villages, it may be mounted on a wagon to be drawn by horses or on a truck to be drawn by the volunteer fire department; whereas if it is built on a large scale as for larger towns and cities, it may be mounted on a truck of its own or carried on the ordinary fire engine, whether the latter be drawn by horses or driven by motor. In any case, however, it is intended that a pump shall be connected to the inlet 18 so that water admitted thereto will be under a certain degree of pressure as will appear below. The exact proportions, materials, and construction of parts may therefore be left to the manufacturer.

It is well known that in order to impregnate water with a gas or chemical which has fire destroying qualities or properties, it must be supplied with certain chemicals in proper proportion, and the chemicals I propose to use are bicarbonate of soda in the cylinder 2 and sulfuric acid within a separate reservoir and flowing constantly into the main tank so that a reaction takes place between the two chemicals and the water in said tank is charged with carbonic acid gas. For this purpose the present apparatus carries an acid reservoir 40 which I propose to make large enough to contain acid sufficient for from twelve to twenty charges of soda as will appear below, and this reservoir has a filling opening 41 at its top closed by a screw cap 42 which in turn is seated with a threaded opening in which is seated a screw plug 43 having through it near its upper end a cross port 44 intersected by an axial port 45 which leads from the cross port 44 down to and opens through the lower end of said plug. The upper end of the latter is by preference squared as shown at 46 so that a key or wrench may be applied thereto. I may say here that this detail is useful for relieving the pressure within the reservoir 40 when it is desired to recharge the latter without discontinuing the stream. By applying a key to the squared upper end 46 and unscrewing the plug 43 until its cross port 44 is exposed, the

pressure within the reservoir blows out; and thereafter a wrench or spanner may be applied to the cap 42 and the latter unscrewed from the opening 41 so that the contents of the reservoir may be replenished. As it is desirable that the acid be kept separate from the soda and in a reservoir of its own so that it cannot become contaminated and cannot spill onto the operator, I prefer to make this reservoir of ample size to contain ten or twenty times the proportion of soda. The charges of the latter within the cylinder 2 may have to be replenished with comparative frequency if the fire is burning so that a constant demand is made on this apparatus, but these details will appear below.

An outlet pipe 50 leads from the reservoir 40 and into the tank 1 near its bottom at the point 51, and in this pipe is a graduated valve 52 by means of which the flow of the acid may be regulated as necessary. While this valve may be of any desired construction, I prefer to provide its hand wheel 53 with a plurality of notches 54 in its edge, and its casing with a finger 55 whose tip springs into said notches so as to hold the valve after it has been set. An equalizing pipe 56 connects the top of the main tank 1 with the top of the reservoir 40, and in this pipe is a cut-off valve 57 of any suitable type.

Another feature of improvement which the present apparatus possesses over my former patent, consists in a pipe 60 connecting the top of the tank 1 with one side of the cylinder 2 at the point 61, and in this pipe is disposed a valve 62 which is preferably of the Kennedy type although I do not wish to be limited thereto. However, I provide a hand lever 63 pivotally connected at one end with the pipe or the casing of this valve and weighted at the other end as at 64, and when this end is raised by hand for a purpose to appear below, the weight will close the valve as soon as the hand is removed—therefore it is impossible for the operator to accidentally leave this valve open. It will be obvious that any suitable type of valve which would act on this principle might be substituted for the form of valve shown in Fig. 1.

Another improvement in the present apparatus consists in providing the charging cylinder 2 with a cage or basket for supporting the soda crystals. Within its lower section I provide a series of stops 70 upon which rests the basket—the latter preferably comprising a perforated disk 71 having an upstanding central tube 72 pierced with perforations 73 which are larger near the disk and grow smaller toward the upper end of the tube, and the upper extremity of the latter carries a spider 74 by which the tube is centered within the cylinder 2

or the upper section thereof as shown in Fig. 3. At about the midlength of this tube it is provided with an external mark in the shape of a pin 75 for a purpose to appear below.

With the parts constructed as described above, the action of this device is as follows: Starting with the main tank and reservoir empty and all valves closed, the cover 4 is loosened and turned aside and a charge of soda crystals placed in the cylinder which is sufficient for a tank of perhaps one hundred and fifty gallons capacity, after which the cover is closed and locked in place. The screw cap 42 is then removed and the reservoir 40 supplied with acid sufficient to contact with from ten to twenty such charges of soda, according to the proportionate size of the reservoir, and the cap replaced and its plug screwed down to close the vents therein. The valve 23 is then opened and water pumped in at the point 18. The valve 39 being closed, the water flows up the bypass pipe 21 and enters the cylinder 2 through the port 3 which is above the charge of soda therein, and such charge is dissolved and washed down through and out of the basket or disk 71, through the check valve 27 at the lower end of the cylinder 2, and onto the perforated plate 16 within the tank 1; the water meanwhile rising in said tank until it stands at a level therein and in the cylinder as can be determined by the mark or pin 75 when the cover 4 is turned aside. It is possible that on the initial charging of this apparatus, the cover may not be closed as above set forth; but after the first charge of soda has been washed out of the cylinder 2 in the manner just described, and saturates or impregnates the water within the tank as indicated in Fig. 1, a second charge of soda is supplied in the same manner to the cylinder 2, excepting that it is not washed out of the same at this time because the cut off valve 23 is closed. During the process as far as has been described I would keep the equalizing pipe 56 closed by means of the valve 57 because there is an affinity between the acid and the soda and it is not yet desirable that they come in contact with each other directly or indirectly.

When now a fire occurs or any occasion arises calling for a stream of water impregnated with the fire-destroying gas, the cut-off valve 57 is opened and the pressure of the air trapped at the top of the tank 1 (which is the same as the water pressure) passes through the pipe 56 into the space above the acid within the reservoir 40. The graduated valve 52 is then opened wide, and the acid, superinduced by the pressure just mentioned, flows freely through the outlet pipe 50 and into the water in the tank 1 beneath the perforated plate 16. This water

is now saturated with soda, reaction between the two chemicals takes place rapidly, ebullition occurs, pressure is set up within the main tank 1 as indicated on the gage 37, and soon this pressure overcomes the water pressure at the inlet 18 but is held in check by the valve 38. Whatever the pressure, it flows through the equalizing pipe 56 and is equalized above and below the acid, so that the latter continues to flow by gravity to the bottom of the tank 1. But as soon as the gage indicates perhaps a hundred and sixty pounds of pressure, I close the graduated valve 52 until the proper notch 54 engages the finger 55, and thereby regulates or graduates the supply of acid to the interior of the tank. This valve may be left so set unless at any time during the operation of the apparatus the gage 37 shows excessive pressure requiring that the valve be closed still further. The supply of acid is at this time graduated to conform with the necessities of the case. That is to say, if the conflagration be a small one, the supply of acid is cut down low; if the fire be a dangerous one as for instance a dwelling or a store, more acid would be admitted; and if it be oil, tar, paint, turpentine, gasoline, or other highly inflammable substances that are burning, I would open the valve 52 still wider so that the water will be charged with a yet larger proportion of acid, in a manner well known to those skilled in this art. However, it may be left to the operator to control this valve as circumstances require, and the proportion of parts and the extraneous conditions such as the weather call for, and the purity and strength of the chemicals make necessary. The outlet valve 30 is now opened, and the chemically treated water issues from the tank under the pressure within the latter and is played through the nozzle on the fire.

To replenish the charge of soda the cover 4 is swung aside and a new charge dropped into the cylinder in the manner above described, after which the cover is closed and fastened and the valve 62 opened by raising its handle lever 63. This permits some of the trapped air under pressure to pass upward through the pipe 60 into the cylinder 2 above the new charge of soda crystals, and the latter are driven down into the basket or onto the disk 71 and the finer particles below it. This valve is then closed and the valve 23 opened, when some of the water passes in at the inlet 3 and the charge is washed downward out of the cylinder 2 in the manner above described. Meanwhile if necessary the graduated valve 52 may be opened a little wider than usual to permit an increased supply of acid at this time, although as above suggested the setting of this valve will depend upon the reading of

the gage 37. The use of the weight 64 on the handle lever 63 will now be obvious. It is intended to hold the valve 62 constantly closed when released, so that the pressure generated in the tank 1 by the mingling of the two chemicals cannot escape into the upper end of the charging cylinder 2. In case the valve 23 should accidentally be left open so that this cylinder fills with water, no injury to the workman will result if he opens the cover 4 at this time, but it would be dangerous to have the valve 62 open except momentarily. This action is repeated from time to time as the charging cylinder 2 needs replenishing with soda crystals, but I prefer to have the reservoir 40 of sufficient capacity to contain acid enough for many rechargings of soda. If the conflagration is a long and tedious one, it may become necessary to replenish the acid in the reservoir, and in that event both valves opening into it are closed before the cap 42 can be removed. The screw plug is withdrawn slightly at this time to expose its ports and relieve the pressure in the top of the reservoir 40, after which the cap 42 can be removed and the acid poured in in a manner which will be clear.

What is claimed as new is:

1. In a chemical fire extinguisher, a main tank, an upright charging cylinder having internal stops, its lower end being connected with the main tank, means for admitting

water to said cylinder, and a removable closure for its upper end; combined with a perforated disk across the interior of said cylinder resting on said stops, an upright tube rising from said disk and provided with perforations which are smaller near the upper end and grow larger toward the lower end of said tube, a spider on the tube for centering the latter within the cylinder, and a pin projecting radially from said tube, for the purpose set forth.

2. In a chemical fire extinguisher, a main tank, an upright charging cylinder having internal stops near its lower end, said end being connected with the main tank, means for admitting water to the upper end of said cylinder, and a removable closure on said end; combined with a perforated disk across the interior of said cylinder resting on said stops, an upright tube rising from said disk and provided with perforations which are smaller near the upper end and grow larger toward the lower end of said tube, and means for centering the latter within the upper portion of the cylinder, for the purpose set forth.

In testimony whereof I have hereunto set my hand in presence of two subscribing witnesses.

EDWARD M. E. HANSEN.
